(57) **CLAIM**

The ornamental design for an attachment for a facial treatment device, as shown and described.

DESCRIPTION

FIG. 1 is a perspective view of an attachment for a facial treatment device, showing the claimed design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is a bottom perspective view thereof.

The broken lines shown in the figures are for the purpose of illustrating portions of the attachment for a facial treatment device that form no part of the claimed design.

1 Claim, 6 Drawing Sheets
